UNITED STATES PATENT OFFICE.

WILLIAM HARLEV, JR., OF CHICAGO, ILLINOIS.

DOOR GUARD AND LOCK.

1,287,978.

Specification of Letters Patent.

Patented Dec. 17, 1918.

Application filed December 6, 1916. Serial No. 135,322.

To all whom it may concern:

Be it known that I, WILLIAM HARLEV, Jr., a citizen of the United States, residing at Chicago, in the county of Cook and State of Illinois, have invented certain new and useful Improvements in Door Guards and Locks, of which the following is a specification.

This invention relates to an attachment 10 for use in connection with doors, for locking them in closed position, and also for holding them against being opened beyond a predetermined amount. Chains and other devices have heretofore been used for the latter purpose, but such chains are apt to mar 15 the door and casing, and the other devices are usually more or less unsightly, and project from the door casing even when not in use.

20 The objects of the present invention are to provide a door guard and lock which will be substantially concealed when not in use; to provide such a device which will be comparatively simple and cheap in construction, 25 and efficient in operation; to provide a lock or guard of this character which may be used on either right or left-hand doors; and to provide such other advantages as will appear more fully from the following description.

30 In the accompanying drawings illustrating this invention:

Figure 1 is a horizontal sectional view of a door and casing, showing my improved guard and lock in the position which it assumes when the door is open;

Fig. 2 is a sectional elevation taken on the line 2—2 of Fig. 1; and

Fig. 3 is a front elevation of the guard and lock, shown in the open position in full lines, 40 and in closed position in dotted lines.

Although the advantages of door guards are well known, their use in connection with high-grade trim has been more or less objectionable, as above suggested, on account 45 of their unsightly appearance and liability of injuring the woodwork. As shown in the accompanying drawings, I provide a combined guard and lock which is set into the casing and is substantially concealed when 50 the door is closed. This device comprises a plate 4, which is bent over at the top to form a flange 5, and is also bent outwardly at the lower end to form a recess 6 for the pivot and for the locking button. The casing 7 is 55 cut away as indicated in the drawings, to re-

ceive the plate 4. The locking arm or member 8 has a slot 9 extending nearly the full length thereof, and thereby forming two branches 10 and 11. One end of the branch 10 is hinged at 12 to a stud 13, which is pivoted to the lower end of the plate 4. This forms a universal joint, so that the locking arm 8 may swing in both vertical and horizontal planes. This arm is also provided at its outer end with a ring or projection 14 for engagement by the finger. The outer end is also provided with a slot 15, which engages with the flange 5 for holding the locking member in closed position. The branch 10 has a projection 16 for engagement with the locking button, for locking the door in closed position. The inner end 17 of the branch 11 is preferably curved as shown, to form a guide for the locking button, to guide it into the slot 9.

The plate 4 is slightly offset to receive the end of a spring 18, which, in the position shown in the drawings, extends downwardly and outwardly, and terminates in a bent or flanged end 19, which extends into the recess 6, just above the upper edge of the locking member when it is in extended position. The plate 4 and spring 18 are held in position by screws 20, some of which are arranged so that their heads will be covered by the locking arm when it is in extended position, so that such screws cannot be readily removed.

The door 21 is provided with a plate 22, secured thereto at a point opposite the recess 6 in the casing. This plate is provided with a projection or button 23, which may be formed integrally therewith or attached thereto in any manner desired. The plate is held by means of screws 24, some of which are also preferably covered by the locking bar 8 when it is in locking position.

When the guard is not in use, the locking arm 8 is swung to the position shown in dotted lines in Figs. 2 and 3, where it is substantially concealed and out of the way. The flange 5 entering the groove 15 will serve to hold the arm in closed position. When the door is closed the button or catch 23 will pass freely below the end 17 of the branch 11, and also below the projection 16 of the branch 10, and into the recess 6. If it is desired to lock the door in this position, the ring or projection 14 is grasped and the arm 8 is swung out to extended position, so

that the projection 16 engages with the button 23, as will be readily seen from Fig. 3, wherein the button is shown in locking position in dotted lines. As the locking arm or bar 8 is swung down, it presses the spring 18 toward the casing, and, as it passes down over the end of the spring, it will be held in the extended position thereby. In this connection it will be noted that there will be sufficient play between the door and the arm 8, so that by moving the outer end of the arm toward the door, it may be swung over enough to partially clear the end of the spring so that it can be swung to its closed position and will depress the spring as it is being moved to such position. It will also be noted that this spring arrangement serves another purpose, whereby the device can be used on either right or left-hand doors. 20 In the drawing the device is shown on a left-hand door, but it may be used on a right-hand door by placing it the other end up. When used in this way, the spring 18 will serve to hold the arm 8 in its locking 25 or extended position.

When the device is to be used as a guard to permit the partial opening of the door, the door is opened a sufficient distance so that the button 23 will clear the projection 30 16, and the arm 8 is then swung down so that the button will enter the open end of the slot 9. This is facilitated by the downwardly curved end 17 of the branch 11, which forms a comparatively wide mouth 35 for the entrance of the button. As soon as the button reaches the end of the slot, as shown in Figs. 1 and 3, it will prevent the further opening movement of the door. It will be noted that the universal joint or 40 hinge of the bar 8 permits the necessary horizontal swinging movement thereof, so that it will remain in engagement with the button without binding.

The various parts of my improved guard 45 and lock may be made of any suitable material, and the form or shape may be changed to suit different conditions, without departing from the scope of this invention, and therefore I do not wish to limit myself to 50 the exact construction or arrangement herein shown and described, except as specified in the following claims, in which I claim:

1. A door guard comprising a plate having a laterally extending flange at one end 55 thereof, a locking arm hinged to the other end of said plate by a universal joint, and adapted to swing in vertical and horizontal planes, said arm having a slot therein extended from the pivoted end to a point adjacent to the other end, and a locking button 60 adapted to be secured to the door and arranged to enter the open end of the slot when the arm is in horizontal position to engage with said slot to limit the opening 65 movement of the door, said arm also having

a slot in the free end thereof for engagement with said flange, to hold the arm in closed position.

2. A door guard comprising a plate having an offset in the lower end thereof, a pivot secured to the offset portion of the plate, an arm hinged to said pivot, said arm having a ring or projection for swinging the same, and having a slot extending to the hinged end, means for fastening said 75 arm in closed position and a catch secured to the door and adapted to pass freely below the lower end of the arm when the arm is in raised position, and to engage with said slot when the arm is swung to locking position.

3. A door guard comprising a plate adapted to be secured to the door casing, a locking arm hinged by means of a universal joint to the lower end of said plate, and adapted to swing in vertical and horizontal planes, means for holding said arm in raised or folded position, said arm having a slot 85 extending from its hinged end to a point adjacent to its outer or free end, and a locking member comprising a button adapted to be secured to the edge of the door, and to engage with a recess in said plate when the door is in closed position, said button being arranged so that it will enter the open 95 end of the slot in said bar when the bar is swung down to horizontal position.

4. The combination with a door having a rabbet in the frame thereof in alinement with the edge of the door, a plate fitting in 100 said rabbet, a locking bar hinged by means of a universal joint to the lower end of said plate, means for holding said bar in raised or folded position, said plate also having a recess below the lower or pivoted end of 105 the bar, said bar also having a slot extending from its hinged end to a point adjacent to its free end, a plate secured to the edge of the door, a button engaging with said plate adapted to enter the recess in the first-named plate when the door is in closed position, and to enter the slot in said bar when the bar is in horizontal position, said plates having screws for holding the same, which are covered by the bar when the bar is in 115 engaging position.

5. A door guard for right and left-hand doors, comprising a plate, a locking arm hinged to said plate and having a slot therein extending from the hinged end to a point 120 adjacent to the other end, means for holding the arm in extended position preparatory to receiving the catch, and a catch secured to the door and arranged to enter the open end of the slot when the arm is in extended position.

6. In a device of the character set forth, the combination of a plate, a locking arm hinged to said plate by a universal joint, and having a slot therein extending from the 130

hinged end to a point adjacent to the other end, a spring secured to said plate and extending outwardly for holding the arm in horizontal or extended position, and a locking member adapted to be secured to the door and to engage with the slot to limit the opening movement of the door.

7. In a combined door guard and lock, the combination of a plate adapted to be secured to the casing between the casing and edge of the door, a locking arm hinged to said plate by a universal joint, said arm having a slot therein extending from the jointed end to a point adjacent to the other end, with a relatively wide mouth at its open end, said arm also having a projection adjacent to the joint for locking the door in closed position, and a catch adapted to be secured to the edge of the door and to engage with either said projection or said slot.

8. In a device of the character set forth, the combination of a plate adapted to be secured to the casing, and having a flange at one end thereof and an offset portion at the opposite end thereof, an arm connected by means of a universal joint to said offset portion, said arm having a groove in the outer end for engagement with said flange, to hold the arm in closed position, a spring connected with said plate for holding the arm in extended position, a catch adapted to be se-

cured to the door, said arm being provided with a projection for engagement with the catch when the door is in closed position, and with a slot for engagement with the catch to permit the door to be opened to a predetermined position.

9. In a door lock and guard, the combination of a hooked locking arm, means for pivoting the arm to the casing, a button secured to the door, said arm having a projection thereon for engagement with the button to lock the door in closed position when the arm is swung to horizontal or extended position, the hooked portion of the arm extending beyond said projection so that it may also be engaged by the button when the arm is in such position.

10. In a device of the character set forth, the combination of a locking arm, means for pivoting the arm to the casing, whereby the arm may be swung to vertical closed, or horizontal extended position, means for holding the arm in extended position, a catch adapted to be secured to the door, a projection on said arm for engagement with the catch when the arm is in extended position, for holding the door closed, said arm also having a slot therein which is adapted to be engaged by the catch for permitting the door to be opened a predetermined amount.
